(57) **CLAIM**

I claim the ornamental design of a survival dog tag, as shown and described.

DESCRIPTION

FIG. 1 is a perspective view of a survival dog tag showing my design;

FIG. 2 is a top view thereof;

FIG. 3 is a bottom view thereof;

FIG. 4 is a top end view thereof;

FIG. 5 is a bottom end view thereof;

FIG. 6 is a left side view thereof; and,

FIG. 7 is a right side view thereof.

The area inside the broken lines in FIGS. 3 and 6 are for environmental purposes only and form no part of the claimed design.
